PASSAGEWAY TUBE FOR AN ANIMAL HABITAT OR SIMILAR ARTICLE

Allan H. Willinger, New Rochelle, and Albert J. Dinnerstein, Brooklyn, N.Y., assignors to Metaframe Corporation, Maywood, N.J.

Filed June 28, 1972, Ser. No. 267,150

Term of patent 14 years

Int. Cl. D30—02

U.S. Cl. D30—1

FIG. 1.

FIG. 2.

FIG. 3.

FIG. 4.

FIG. 1 is a side elevational view of a passageway tube for an animal habitat or similar article, showing my new design, the opposite side being substantially a mirror image thereof;

FIG. 2 is an end elevational view, the opposite end being substantially a mirror image thereof;

FIG. 3 is an exploded end elevational view; and

FIG. 4 is an interior side elevational view, the opposite interior side being substantially a mirror image thereof.

The drawing figures are diagonally lined to indicate transparency.

We claim:

The ornamental design for a passageway tube for an animal habitat or similar article, as shown and described.
